(57) **CLAIM**

We claim the ornamental design for a golf cart dash cover, as shown and described.

DESCRIPTION

FIG. 1 is a left front perspective view of a golf cart dash cover, showing our new design.

FIG. 2 is a top, left, front perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing a golf cart in FIG. 1 illustrates environmental structure that forms no part of the claimed design.
